CLAIM

We claim, the ornamental design for a confectionery, as shown and described.

DESCRIPTION

FIG. 1 is a perspective view of a confectionery, showing our new design in a first embodiment;

FIG. 2 is a front view of the embodiment shown in FIG. 1;
FIG. 3 is a rear view of the embodiment shown in FIG. 1;
FIG. 4 is a side view of the embodiment shown in FIG. 1;
FIG. 5 is another side view of the embodiment shown in FIG. 1;

FIG. 6 is a top view of the embodiment shown in FIG. 1;
FIG. 7 is a bottom view of the embodiment shown in FIG. 1;

FIG. 8 is a perspective view of a confectionery, showing our new design in a second embodiment;

FIG. 9 is a front view of the embodiment shown in FIG. 8;
FIG. 10 is a rear view of the embodiment shown in FIG. 8;
FIG. 11 is a side view of the embodiment shown in FIG. 8;
FIG. 12 is another side view of the embodiment shown in FIG. 8;

FIG. 13 is a top view of the embodiment shown in FIG. 8;
FIG. 14 is a bottom view of the embodiment shown in FIG. 8;

FIG. 15 is a perspective view of a confectionery, showing our new design in a third embodiment;

FIG. 16 is a front view of the embodiment shown in FIG. 15;
FIG. 17 is a rear view of the embodiment shown in FIG. 15;
FIG. 18 is a side view of the embodiment shown in FIG. 15;
FIG. 19 is another side view of the embodiment shown in FIG. 15;

FIG. 20 is a top view of the embodiment shown in FIG. 15;
FIG. 21 is a bottom view of the embodiment shown in FIG. 15;

FIG. 22 is a perspective view of a confectionery, showing our new design in a fourth embodiment;

FIG. 23 is a front view of the embodiment shown in FIG. 22;
FIG. 24 is a rear view of the embodiment shown in FIG. 22;
FIG. 25 is a side view of the embodiment shown in FIG. 22;
FIG. 26 is another side view of the embodiment shown in FIG. 22;

(Continued)

FIG. 27 is a top view of the embodiment shown in FIG. 22; and,
 FIG. 28 is a bottom view of the embodiment shown in FIG. 22.
 The broken lines shown in the drawings illustrate portions of the confectionery that form no part of the claimed design.
